UNITED STATES PATENT OFFICE.

CHARLES F. PRICHARD, OF NEW BRITAIN, CONNECTICUT.

CHIMNEY-CAP.

No. 798,700.

Specification of Letters Patent.

Patented Sept. 5, 1905.

Application filed January 11, 1905. Serial No. 240,578.

To all whom it may concern.

Be it known that I, CHARLES F. PRICHARD, a citizen of the United States, residing at New Britain, in the county of Hartford and State 5 of Connecticut, have invented certain new and useful Improvements in Chimney-Caps, of which the following is a specification.

My invention relates to improvements in chimney-caps; and the objects of my improvements are cheapness of construction, convenience of transportation and setting, and efficiency and durability when set.

In the accompanying drawings, Figure 1 is a central vertical section of my chimney-cap 15 on the line xx of Fig. 3. Fig. 2 is a vertical section of the same on the line yy of Fig. 3 with the central flue in side elevation. Fig. 3 is a reduced plan view of the base of my chimney-cap.

20 I form my chimney-cap of a mineral composition of which cement may constitute a substantial part. For convenience of manufacture, transportation, and setting the cap in place on a chimney I form the same of several parts. I prefer also to give the cap such a form that it will serve as a substitute for the ordinary expanded or flaring topped-out portion of the chimney, such as masons lay with brick and mortar. When this is the 25 case, the masons in laying a new chimney will carry it up with straight and plain sides without any enlargement until it reaches a given height and then surmount the same with one of my caps. When it is placed on an old chimney, the top courses of brick may be removed down to the said plain straight portion and my cap placed thereon. The top courses of the brick in the plain straight portion 30 upon which to place the cap, is shown in Fig. 35

40 1. As shown, my cap is formed of four parts or pieces, the base A, middle outer section B, cap C, and central flue D.

The base A has plain sides 4 of the same external dimensions as the plain straight portion 45 3 of the chimney and a projecting bottom band 5 to imitate the ordinary projecting course of brick that form an ornamental band at this point of the chimney. The base A is also provided with a cross member 6, leaving 50 two flues or openings 7, that lead from the interior of the chimney. The said cross mem-

ber is also provided with a conical cavity 8, within which is seated the lower end of the central flue D. A suitable drip channel or opening 9 leads from this cavity 8 to the exterior of the base, as shown in Figs. 1 and 2 and as indicated by broken lines in Fig. 3. The cap C is centrally perforated for the reception of the upper end of the central flue D. This flue is preferably made of a tapering form at its lower end for being seated in the cross member of the base, as shown. It is provided with side openings 10, as shown. I have shown this central flue as of a length that projects slightly above the top of the 65 cap; but it is evident that it may be longer, so as to project any desired distance above the said top. I also prefer to provide the middle outer section B and cap C each with a flange 11 for shutting down over the part on which 70 they rest, as shown.

In setting the cap the base A is first put in place on the chimney portion 3, and then the outer middle section B may be put on. It will be the most convenient to next set the 75 central flue D and finally put on the cap C. The products of combustion will pass up from the chimney through the flues 7 into the middle outer section B, then through the openings 10 into the central flue D, and out through 80 the top of the said flue at the top of the cap. This will keep the said flue warm, so as to insure a good draft. The products of combustion will pass out of the top instead of at the side, and at the same time the cap is storm-proof, so that no water can run down the chimney. By dispensing with side exits the liability of a downward current is avoided. A small amount of air may sometimes enter 85 through the drip-channel 9; but it will pass upwardly through the central flue without any detrimental effect. On the contrary, its tendency will be to increase the draft. While it is always preferred to use the central flue with my chimney-cap, it is evident that the 90 cap is a practically operative one with this central flue omitted.

I claim as my invention—

1. The herein-described chimney-cap, consisting of the composition base A, composition middle outer section B, and composition cap C all formed to sit one over the other 100

with the exit at the top, the said base having the band 5 to mark the junction of the straight and topped-out portions of the chimney.

2. A chimney-cap comprising the base A 5 with a cross member having a flue-seat, the middle outer section, the central flue resting on the said cross member and extending up through the said middle outer section, and the

cap seated on the said middle outer section and fitted to the upper end of the said central 10 flue.

CHARLES F. PRICHARD.
